CLAIM

The ornamental design for a button activated audible bible verse speaker, as shown and described.

DESCRIPTION

FIG. 1 is a top perspective view of a button activated audible bible verse speaker;

FIG. 2 is a bottom perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.
